TUCKING AND FOLDING MECHANISM FOR
WRAPPING MACHINES

Charles Arelt, Richmond Hill, N. Y., assignor to
American Machine and Foundry Company, a
corporation of New Jersey

Application February 3, 1943, Serial No. 474,528

25 Claims. (Cl. 93—2)

This invention relates to wrapping machines suitable for wrapping any article, such as bread, and consists chiefly in improvements in the mechanism for folding the wrapper about such articles especially insofar as it concerns the formation of the initial wrapper folds about each article.

The subject matter of this invention relates primarily to wrapping machines of the general type shown in Schmitt Patent No. 1,851,295, granted March 21, 1932, in which articles being wrapped are moved against a draped wrapper onto a lifter table, raised and transported through the machine, although the mechanism shown and described is readily adaptable for use in other types of wrapping machines.

In this type of machine the first end folds or tucks are usually made as the article, such as a loaf of bread, either is moved by means of an infeed conveyor against a draped wrapper onto a lifter table, or after it is positioned thereon. As the article travels onto the lifter table or after it is positioned thereon, a pair of end tucker members engage the ends of the wrapper projecting beyond the ends of the loaf of bread, fold the same in against the end of the loaf, and also partially form the bottom end flap or the last fold to be made. It so happens that during the formation of this last-mentioned flap there is a tendency for the paper to bow or curl upward towards the ends of the loaf, which bow or curl may result in an imperfectly formed flap as the loaf is moved past the several folding elements of the machine.

According to my invention I have provided mechanism which takes into consideration the fact that articles such as loaves of bread may vary in size and therefore contribute somewhat to the formation of improper folds and the formation of bowed or curled flap portions as mentioned hereinabove. In order to overcome this difficulty I have provided mechanism which operates on each partially folded bottom end flap and exerts a positive flattening or creasing force thereon in order to prepare such wrapper parts for better folding and thereby prevent the formation of mal-formed and unsatisfactory folds so that the over-all appearance of the package is much improved.

My invention also consists in the provision of improved mechanism for forming the first end folds about a package and means for maintaining the end folder members parallel with respect to the ends of the article being wrapped and imparting thereto straight line movement during the formation of the folds.

It is a further object of my invention to provide improved end folding mechanism for forming the first end folds in the wrapper being wrapped about an article and to provide for coaction therewith, mechanism for flattening and creasing other end portions of the wrapper in order that subsequent folds may be better formed and a more efficient, better appearing package result.

- 5 10 15 20 25
- It is also an object of my invention to provide improved end folding mechanism mounted for travel with a lifter table whereby certain of the folding means, such as the end tuckers which form the first folds of each package being wrapped, move parallel with and inwardly towards the ends of the article being wrapped in order to prevent damage to the wrapping material, and generally improve the formation of the first end folds.
- 30 35 40 45
- My invention also includes an article lifter table having vertically movable members coacting with the horizontally movable end tuckers for flattening and creasing portions of the wrappers which constitute subsequent end flaps and thereby effect the formation of better flaps and more perfectly sealed packages.

It is also an object of my invention to provide improved end folding and creasing mechanism mounted on a lifter table and operable to form first end folds and crease other portions of a wrapper extending beyond the ends of an article to be wrapped. My invention also contemplates the provision of improved stationary folders positioned to coact with the end folders and creasers carried by the lifter table, and means for effecting relative movement between the creasers and lifter table for creasing partially formed bottom flaps.

My invention also consists in the provision of end folders mounted on an article conveyor, such as a lifter table, and creaser and wrapper flattening means associated therewith for moving the end folders and creasing and flattening means in proper timed relation in the formation of improved packages.

It is an added object of my invention to provide stationary end folders mounted in the path of movement of a lifter table, which folders have wrapper flap guide means formed on or attached thereto for guiding a portion of the wrapper extending beyond the ends of an article being wrapped, and coact with end creasing members carried by the lifter table in guiding unfolded portions of a wrapper and forming better end folds.

With these and other objects not specifically mentioned in view, the invention consists in certain combinations and constructions which will be hereinafter fully described, and then set forth in the claims hereunto appended.

In the accompanying drawings which form a part of this specification, and in which like characters of reference indicate the same or like parts:

Figure 1 is a side elevation of the novel end folding mechanism constituting this invention;

Figure 2 is a plan view of the same mechanism;

Figure 3 is a partial plan view illustrating the direction of travel of the end folders relative to the end of an article;

Figure 4 is a partial sectional end elevation showing the relationship between the end folder and the creaser or flattening members;

Figure 5 is a partial perspective view of the same general arrangement as shown in Figure 4;

Figure 6 is a partial side elevation illustrating a modified form of device for actuating the wrapper fold flattening or creasing members; and

Figure 7 is a plan view of the elevation shown in Figure 6.

Referring to the drawings which show a preferred embodiment of my invention, the side frames 20 of the wrapping machine support cross shafts 22, 24 and 26, shaft 22 being suitably driven from the main drive shaft of the machine (not shown). Mounted on shaft 22 is a cam 26 provided with a track 28 on which runs a cam follower 30 mounted on lever 32 swingably supported on shaft 24. To one arm of lever 32 is pivotally connected an adjustable rod 34 which in turn is connected at 38 to the lifter table 40 swingably mounted on shaft 26 for movement between article receiving position, adjacent the in-feed guide designated generally 44, and article discharge position adjacent foldway 46. An in-feed conveyor or pusher 48 is reciprocated by suitable means (not shown) to feed articles over guide 44 against a wrapper W fed from a suitable source of supply (not shown) over a guide plate 50 and draped in the path of articles to be wrapped. Mechanism for feeding and positioning wrappers in the path of articles moving onto the lifter table 40, and the infeed pusher may be constructed and operated in the manner shown in the above referred to Schmitt patent. Since these mechanisms form no specific part of the invention further description and showing is deemed unnecessary.

As shown in Figures 1, 2 and 3, the infeed pusher 48 in moving an article A and wrapper W onto lifter table 40 causes the wrapper to be partially encircled about the article with the depending end of the wrapper positioned beneath the article in the usual manner.

The lifter table 40 is provided with a back tension plate designated generally 45 and a top tension plate 47 which may be similar in construction and operation to those shown in said Schmitt patent.

As shown in Figures 2, 3, 4 and 5, portions of the wrapper extend outwardly beyond the ends of an article A to be wrapped. The first end folds I preferably are made as an article is moved onto lifter table 40. However, if desired these end folds can be made after an article is positioned thereon. The first end folds are made by means of opposed end folders 54 which are mounted for travel with the lifter table between article receiving and article discharge positions. Since

each of the end folder units U is identical, but one will be described in detail.

End folders 54 are timed to move towards the ends of an article moving onto the lifter table 40 in such a way that these folders are located in an innermost position above the article A which is fully positioned on lifter table 40. In this way flat first folds are assured because the wrapper is drawn positively against the ends of the article. Complete folding of the wrapper is accomplished as a result of the lifter table moving to discharge position in alignment with foldway 46 and as each partially wrapped article is moved from the lifter table by means of one of a number of flights 52 carried by conveyor 53 of the same type and construction, as shown in the above referred to Schmitt patent, over foldway 46 and past end folders 49 and 51 which make end folds III and IV, respectively.

Each end folder unit U is mounted above the lifter table for movement therewith between article receiving and discharge positions by means of a slideable support member 60 carried on shaft 26 and provided with a reduced portion 62 in which rides a lug 64 on hub 66 adjustably mounted on right-left hand threaded rod 68 journalled in side frames 20 and provided with a manually operated knob 69 for adjusting the position of units U and folders 54 on the table 40 according to the length of article being wrapped. Member 60 has a bracket 70 provided with a flat vertical portion 72 angularly inclined with respect to the longitudinal axis of the machine, and fixed to portion 72 adjacent the top and bottom by screws 74 are opposed gibbs 76 having substantially V-shaped portions 78 which form guides for a slide 80.

Secured to slide 80 by screws 82 and mounted for movement therewith is a bracket 84 pivotally connected at 88 to a link 90. Link 90 is also pivotally connected at 92 to one arm 93 of a bell crank lever 94 fulcrumed on a headed stud 96 fast in member 60 (Figure 2). End folders 54 are secured to bracket 84 by screws 85. Arm 95 of lever 94 is provided with a depending pin 98 mounting a cam roller 100 running in a track formed of two spaced bars 102 secured by screws 104 to spaced flanges 106 formed in one end of lever 108. Lever 108 is fulcrumed on shaft 26 between forks 41 of lifter table 40. The lifter table and lever 108 are maintained in operative position on shaft 26 by means of collars 43 fixed to shaft 26 (Figure 2).

Lever 108 is also provided with a fork 110 in which is positioned a shoe 112 pivotally connected to a stud 114 fixed in arm 116 of bell crank lever 118 mounted on shaft 120 suitably journalled in ribs 121 on the underside of lifter table 40. Arm 122 of lever 118 carries a cam follower 124 tracking a cam 126 keyed at 127 to shaft 22. Cam 126 carries an adjustable plate 128 which by means of screws 130 is secured on cam 126 in any desired position to control the time at which the end folders move towards the ends of an article being wrapped to make the first folds I. In this way adjustments can be made in accordance with the width of articles being wrapped. Since plate 128 cannot be adjusted beyond the leading end of cam 126, as seen in Figure 1, the time of opening the folders remains unchanged at all times.

It follows therefore that while cam follower 124 runs on cam 126, the folders 54 are held open. However when follower 124 runs off cam 126, spring 132 having one end fastened to pin 134 carried by lifter table 40 and its other end

secured to an adjustable pin 136 in arm 116 causes lever 108 to rock counterclockwise as viewed in Figure 1, thereby causing slides 80 and folders 54 to move inward to folding position. In the illustrated embodiment the movement of the folders is so timed with respect to infeed conveyor 48 that the folders 54 complete end folds I (Figures 2, 3, 4 and 5) just after an article has been positioned on table 40. Cam follower 124 is maintained free of contact with cam 126 when lifter table 40 is raised. Tension in spring 132 is varied by turning threaded rod 136 relative to nut 138. Arm 116 of lever 108 is provided with an adjustable set screw 140 coacting with a stop lug 142 on the underside of lifter table 40 to control the amount of inward movement of end folders 54 and creasing and/or flap flattening members 150 described in detail hereinbelow.

Mounted exteriorly of and cooperating with end folders 54 are bottom end flap creasing and/or flattening members 150 which assist materially in the pre-forming of the bottom end flaps IV. These members operate to remove from the partially formed bottom end folds IV, or that portion of the wrapper extending outwardly beyond and adjacent the ends of an article, bulges, curls or bows, and prevent generally wrinkling or crushing thereof which might occur otherwise during wrapping operations, especially in machines operating at high speeds. In articles such as loaves of bread where there are often some variations in dimensions, and shapes, these members contribute to the solution of the problem of properly disposing the projecting ends of wrappers and forming more uniform end folds. Although there are two flattening and creasing members, since they are identical in construction and operation, only one will be described in detail. A pin 152 secured in bracket 84 provides a fulcrum for the creaser and/or wrapper flattening member 150 described more in detail herein-after. As shown in Figures 1 and 2, creaser member 150 is provided with an extension or lug 153 supporting a pin 154 to which is connected one end of a spring 156, the other end of which is secured to a pin 158 also mounted in bracket 84 (Figures 1 and 2). A stop pin 160 in bracket 84 limits upward movement of member 150 under the action of spring 156. Each creaser or flattener member 150, which is preferably provided with a vertical face 162 and a flat face 164 (Figures 1, 2 and 5), is adapted to move to and from the lifter table 40. Each member 150 adjacent its free end may also be provided with a cut out portion 155 and a substantially vertically extending part 151, the functions of which are described hereinafter.

It will be evident that due to the mounting of end folder units U on diagonally positioned slides 80, each folder 54 is given a straight line motion towards the ends of each article moving onto the lifter table, and at the same time each end tucker is maintained in a plane substantially parallel to the planes defining the ends of the article being wrapped. Also each member 150 is located for operation as the result of the inward travel of slides 80.

After the completion of the first end folds I the lifter table is elevated, and in moving from article receiving to article discharge position, the second end folds II are made in the projecting wrapper ends adjacent the top of the article by means of stationary folders 166 secured by screws 168 to frames 170 mounted for adjustment to and from each other in any well known

manner, such as disclosed in co-pending Jensen application, Serial No. 225,697, filed August 19, 1938. As shown, right-handed threaded rods 172 journaled in side frames 20 are manually adjustable by hand knob 174 to position frames 170 and folders 166 properly along foldway 46.

Each of the frames 170, adjacent folders 166 is provided with a bolt 176 adjustably secured therein by means of nut 179 and depending therefrom into the path of movement of members 150 (Figure 1). Each bolt 176 has mounted at its free end a stop, such as a rubber cap 177, which when the lifter table is raised a sufficient distance causes the creaser and/or flat flattening member 150 to be moved downwardly against the tension of spring 156 towards lifter table 40 in order to flatten and/or crease that portion of the wrapper extending beneath end folders 54 adjacent the bottom of the ends of each article being wrapped. In this manner it will be seen that even though there may be a tendency during the initial operation for a portion of the wrapper adjacent the ends of the article to bulge, bow or curl upwardly, the action of the members 150 flattens and smooths out such bulges, bows and curls and insures the formation of better and more uniform bottom flaps IV so that when flights 52 move each partially wrapped article off the lifter table onto foldway 46 and the bottom flaps IV are completed by stationary folders 51, danger of crumpling or rupture of the bottom portions of the wrapper is substantially eliminated. Bolts 176 are so adjusted that members 150 in operative position are spaced from lifter table 40 and wrapper portions X (Figures 4 and 5) are loosely held therebetween and free to move with the article without pulling or twisting or damage thereto as the article is moved onto foldway 46.

40 In order to insure better disposition of that portion of the wrapper extending downwardly between the lifter table and foldway 46, folders 166 preferably are provided with outwardly and downwardly projecting wings 167 which coact with vertical portions 151 on members 150. During the upward movement of the lifter table 40 relative to stationary folder 166, wings 167 are accommodated by cut out portions 155 in the members 150 and the unfolded vertical projecting portion of the wrapper is guided by the wall 169 of wings 167 and portion 151 of creaser members 150. When, therefore, the lifter table reaches the article discharge position in which it is in alignment with foldway 46, the first and second end folds I, II have been completed, that portion of the bottom flap IV adjacent the first fold is flattened and/or creased, and the article is then transferred by means of one of the conveyor flights 52 past pivotally mounted, stationary folders 49 mounted on frames 170. Folders 49 swing on pivots 180 in the direction of travel of the article against the action of springs 181 and form the third fold III, after which the last or bottom flap IV is folded upwardly against the end of the article by stationary folders 51. Folders 49 are provided with curved shoes 182 which tend to press down portions of the bottom end flaps, and operate in conjunction with complementary spaced shoes 184 on folder support plates 186.

Figures 6 and 7 show a modified form of device for effecting positive movement of members 150. Since this device is identical in both of the end folder units, but one has been shown and described. Each tucker unit U is provided with a

ball headed pin 190 mounted in and projecting from lower gib 76. Each ball head forms a ball and socket connection 192 with one end of an adjustable rod 194 pivotally connected at its other end to arm 196 of lever 198 fulcrumed on pin 152. Arm 200 of lever 198 is provided with an adjustable set screw 202 positioned to engage an abutment 204 on member 150.

In operation, when end folders 54 are moved inwardly into operative position relative to the ends of an article being wrapped, members 150 are retained in inoperative position against stops 160 by springs 156 until slides 80 approach their innermost position, at this time due to the relative movement of the several parts described hereinabove, levers 198 are rocked on their fulcrums 152 thereby causing set screws 202 to engage abutments 204 and move members 150 into engagement with wrapper portions X which extend outwardly beyond the ends of the article beneath folders 54 (Figures 4 and 5). Set screws 202 are so adjusted that members 150 operate at substantially the same time that end folds I are completed and members 150 are moved into such operative position relative to lifter table 40 that wrapper portions X therebeneath are free to slide therefrom when a partially wrapped article is moved from table 40 onto foldway 46.

The invention above described may be varied in construction within the scope of the claims, for the particular device, selected to illustrate the invention, is but one of many possible concrete embodiments of the same. It is not, therefore, to be restricted to the precise details of the structure shown and described.

What is claimed is:

1. In a wrapping machine, a lifter table constructed and arranged to receive a partially wrapped article having end portions of the wrapper extending beyond the ends of said article, and deliver the same to a discharge position, end tuckers carried by said lifter table, means for moving said tuckers into folding engagement with portions of said projecting wrapper to form end tucks and partially form other flaps extending beyond the ends of said article adjacent said table, flap flattening members located adjacent said tuckers, and means for moving said members towards said table for flattening said partially formed flaps against said table.

2. In a wrapping machine, a lifter table constructed and arranged to receive a partially wrapped article with end portions of the wrapper extending beyond the ends of said article, means for moving said table to deliver said partially wrapped article to a discharge position, end tuckers carried by said table, means for moving said tuckers into engagement with portions of said wrapper to form end flaps therein, flap creasing members also carried by said table, and means for effecting relative movement between said members and table to crease and flatten other portions of said wrapper ends.

3. In a wrapping machine having a lifter table, and an infeed conveyor for moving an article against a draped wrapper onto said table and positioning said article on said table with said wrapper partially encircling said article with portions of said wrapper extending unfolded beyond the ends of said article, opposed end folders mounted on said table, means for moving said folders towards the ends of said article to fold a portion of said extending wrapper portions against each end of said article, means for moving said table

and delivering said partially wrapped article to discharge position, spaced folders located to engage other portions of said wrapper and fold the same against the ends of said article during the movement of said table, end creasers carried by said table, and means operative during the movement of said table for moving said creasers towards said table to flatten and crease other parts of said extending wrapper portions.

10 4. In a wrapping machine having a lifter table, and an infeed conveyor for moving an article against a draped wrapper onto said table and positioning said article on said table with said wrapper partially encircling said article with portions of said wrapper extending unfolded beyond the ends of said article, opposed end folders mounted on said table, means for moving said folders towards the ends of said article to fold a portion of said extending wrapper portions against each end of said article, means for moving said table and delivering said partially wrapped article to discharge position, spaced folders located to engage other portions of said wrapper and fold the same against the ends of said article during the movement of said table, wrapper creasing members located adjacent said end folders and coacting therewith, means mounting said members for movement towards said table, means carried by said spaced folders for effecting movement of said members towards said table as said table is moved to delivery position, and guide means on said members coacting with said guide means on said stationary folders for controlling the disposition of part of the unfolded portion 30 of the wrapper extending beyond the ends of said article.

5. In a wrapping machine having a lifter table, and an infeed conveyor for moving an article against a draped wrapper onto said table and positioning said article on said table with said wrapper partially encircling said article with portions of said wrapper extending unfolded beyond the ends of said article, opposed end folders mounted on said table, means for moving said folders towards the end of said article to fold a portion of said extending wrapper portions against each end of said article, means for moving said table and delivering said partially wrapped article to discharge position, spaced folders located to engage other portions of said wrapper and fold the same against the ends of said article during the movement of said table, pivoted wrapper creasing members carried by said table, means normally holding said members in inoperative position away from said table, and means for swinging said members downwardly into operative position relative to said table.

6. In a wrapping machine having a lifter table, and an infeed conveyor for moving an article against a draped wrapper onto said table and positioning said article on said table with said wrapper partially encircling said article with portions of said wrapper extending unfolded beyond the ends of said article, opposed end folders mounted on said table, means for moving said folders towards the ends of said article to fold a portion of said extending wrapper portions against each end of said article, means for moving said table and delivering said partially wrapped article to discharge position, spaced folders located to engage other portions of said wrapper and fold the same against the ends of said article during the movement of said table, movably mounted wrapper flattening and creasing

members carried by said table, means mounting said members exteriorly of said end folders, resilient means normally holding said members spaced from said table, and means for moving said members towards said table for holding down a portion of said wrapper.

7. In a wrapping machine having a lifter table, and an infeed conveyor for moving an article against a draped wrapper onto said table and positioning said article on said table with said wrapper partially encircling said article, and portions of said wrapper extending unfolded beyond the ends of said article, opposed end folders mounted on said table, means for moving said folders to and from said article for forming end folds, creasers having flat wrapper engaging faces provided with openings therein adjacent one end movably mounted on said table adjacent said folders, stationary folders mounted in the path of movement of said article as said table is moved to a delivery position, and wrapper guide means on said stationary folders projecting outwardly therefrom constructed and arranged to coact with said openings in said creasers in guiding and creasing parts of said wrapper.

8. In a wrapping machine having a lifter table, and an infeed conveyor for moving an article against a draped wrapper onto said table and positioning said article on said table with said wrapper partially encircling said article and portions of said wrapper extending unfolded beyond the ends of said article, means for moving said table and said partially wrapped article to a discharge position, opposed end folders carried by said table, creasers movably mounted on said table, means locating said creasers adjacent said folders, stationary folders mounted in the path of movement of said article as said table is moved to said discharge position, wrapper guide members on said stationary folders projecting outwardly therefrom, and guide means on said creasers coacting with said guide members for controlling the position of unfolded wrapper portions extending beyond the ends of said article.

9. In a wrapping machine, a lifter table, means for moving said table from article receiving to article discharge position, an infeed conveyor adapted to move an article against a wrapper onto said lifter table at said article receiving position to partially encircle said article and provide extending wrapper portions for folding against the ends of said article, opposed end folders, means mounting said folders on said table adjacent the ends of said article, means for moving said folders to engage and fold portions of said wrapper against the ends of said article, stationary folders mounted in the path of travel of said table adapted to form other folds in said wrapper upon the ends of said article during the travel of said table from receiving to discharge position, wrapper creasing and fold flattening members carried by said table and mounted for movement with said folders to and from the ends of said article, and means for effecting relative movement between said last-named folders and members to flatten and crease portions of the wrapper extending beyond the ends of said article adjacent said table.

10. In a wrapping machine having an article lifter table, and means for positioning a partially wrapped article thereon with portions of said wrapper extending beyond the ends of said article, end folders carried by said table, means for moving said folders into engagement with portions of said wrapper to form end tucks there-

in, and flap creasing members carried by said table and movable relative to said tuckers and table for creasing portions of said wrapper extending outwardly beneath said tuckers.

- 5 11. In a wrapping machine having an article lifter table, and means for positioning a partially wrapped article thereon with portions of the wrapper extending beyond the ends of said article, opposed end folders carried by said table, supports for said folders, said supports including spaced brackets and means mounted on said brackets for moving said folders with a straight line motion in one plane while maintaining said folders at all times substantially parallel to the ends of said article, end creasers also carried by said table, means mounting said creasers adjacent and exteriorly of said end folders, and means for effecting movement of said creasers towards said table in a plane substantially at right angles to the path of movement of said end folders.
- 10 12. In a wrapping machine having an article lifter table, and means for positioning a partially wrapped article thereon with portions of the wrapper extending beyond the ends of said article, end folders carried by said table, means for moving said folders into engagement with portions of said wrapper to form end folds therein, flap creasers mounted adjacent and exteriorly of said folders, and means operative after said folders have formed said end folds for effective relative movement between said table and creasers for creasing other portions of the wrapper.
- 15 13. In a wrapping machine, a lifter table constructed and arranged to support a partially wrapped article, opposed end folders mounted on said table, and mechanism for moving said folders with a straight line motion to and from a folding position relative to the ends of said article, said mechanism including means for maintaining said tuckers substantially parallel to the ends of said article during the operation of said mechanism.
- 20 14. In a wrapping machine, a lifter table constructed and arranged to support a partially wrapped article, opposed end folders mounted on said table, mechanism for moving said folders with a straight line motion to and from a folding position relative to the ends of said article, said mechanism including means for maintaining said tuckers substantially parallel to the ends of said article during the operation of said mechanism.
- 25 15. In a wrapping machine, a lifter table constructed and arranged to support a partially wrapped article, opposed end folders mounted on said table, mechanism for moving said folders with a straight line motion to and from a folding position relative to the ends of said article, said mechanism including means for maintaining said tuckers substantially parallel to the ends of said article during the operation of said mechanism.
- 30 16. In a wrapping machine, a lifter table constructed and arranged to support a partially wrapped article, opposed end folders mounted on said table, mechanism for moving said folders with a straight line motion to and from a folding position relative to the ends of said article, said mechanism including means for maintaining said tuckers substantially parallel to the ends of said article during the operation of said mechanism.
- 35 17. In a wrapping machine, a lifter table constructed and arranged to support a partially wrapped article, opposed end folders mounted on said table, mechanism for moving said folders with a straight line motion to and from a folding position relative to the ends of said article, said mechanism including means for maintaining said tuckers substantially parallel to the ends of said article during the operation of said mechanism.
- 40 18. In a wrapping machine, a lifter table constructed and arranged to support a partially wrapped article, opposed end folders mounted on said table, mechanism for moving said folders with a straight line motion to and from a folding position relative to the ends of said article, said mechanism including means for maintaining said tuckers substantially parallel to the ends of said article during the operation of said mechanism.
- 45 19. In a wrapping machine, a lifter table constructed and arranged to support a partially wrapped article, opposed end folders mounted on said table, mechanism for moving said folders with a straight line motion to and from a folding position relative to the ends of said article, said mechanism including means for maintaining said tuckers substantially parallel to the ends of said article during the operation of said mechanism.
- 50 20. In a wrapping machine, a lifter table constructed and arranged to support a partially wrapped article, opposed end folders mounted on said table, mechanism for moving said folders with a straight line motion to and from a folding position relative to the ends of said article, said mechanism including means for maintaining said tuckers substantially parallel to the ends of said article during the operation of said mechanism.
- 55 21. In a wrapping machine, a lifter table constructed and arranged to support a partially wrapped article, opposed end folders mounted on said table, mechanism for moving said folders with a straight line motion to and from a folding position relative to the ends of said article, said mechanism including means for maintaining said tuckers substantially parallel to the ends of said article during the operation of said mechanism.
- 60 22. In a wrapping machine, a lifter table constructed and arranged to support a partially wrapped article, opposed end folders mounted on said table, mechanism for moving said folders with a straight line motion to and from a folding position relative to the ends of said article, members provided with flat creasing faces mounted on said table, means for positioning said members in creasing position, and means for moving said members vertically to and from said table for flattening and creasing portions of said wrapper.
- 65 23. In a wrapping machine, a lifter table constructed and arranged to support a partially wrapped article, opposed end folders mounted on said table, mechanism for moving said folders with a straight line motion to and from a folding position relative to the ends of said article, members provided with flat creasing faces mounted on said table, means for positioning said members in creasing position, and means for moving said members vertically to and from said table for flattening and creasing portions of said wrapper.
- 70 24. In a wrapping machine, a lifter table movable to and from an article receiving and an article discharge position, said table being constructed and arranged to support a partially wrapped article, opposed end folders mounted on said table, mechanism for moving said folders to

and from the ends of said article for forming end folds in portions of said wrapper, stationary folders located in the path of movement of said article on said table for forming folds in other portions of said wrapper, wrapper guide members mounted on said stationary folders and projecting outwardly therefrom, wrapper flattening and creasing devices having flat wrapper engaging faces provided with an opening permitting relative movement between said members and said devices mounted on said table, and means for moving said devices vertically to and from said table.

17. In a wrapping machine, a lifter table movable to and from an article receiving and an article delivery position, and constructed and arranged to support a partially wrapped article, opposed end folders mounted on said table, mechanism for moving said folders with a straight line motion to and from folding position relative to the ends of said article, said mechanism including means for maintaining said tuckers at all times substantially parallel to the ends of said article, stationary folders mounted in the path of movement of said articles on said table for forming other folds in portions of said wrapper, and guide members on said stationary folders for guiding portions of said wrapper remaining unfolded.

18. In a wrapping machine, a lifter table constructed and arranged to support a partially wrapped loaf of bread having a wrapper partially encircled thereabout with end portions of the wrapper extending beyond the ends of said load, opposed end tuckers, supports for said tuckers mounted on said table, flap creasing means mounted on said supports, and means operating in timed relation to the movement of said tuckers for effecting relative movement between said creasing means to and from said table.

19. In a wrapping machine, a conveyor for an article to be wrapped, said conveyor having an article supporting surface means for moving an article against a wrapper positioned in the path of travel of said article to thereby partially enclose said article in said wrapper, and depositing said partially wrapped article on said article supporting surface of said conveyor means for moving said conveyor between article receiving and delivery positions, opposed end folders, means mounting said folders on said conveyor for movement therewith, and means for moving said folders with a straight line movement above said supporting surface into and out of engagement with portions of said wrapper extending beyond the ends of said article to form end folds therein.

20. In a wrapping machine, a conveyor for an article to be wrapped, said conveyor having an article supporting surface, means for moving an article against a wrapper positioned in the path of travel of said article to thereby partially enclose said article in said wrapper, and depositing said partially wrapped article on said article supporting surface of said conveyor, means for moving said conveyor between article receiving and delivery positions, opposed end folders, means mounting said folders on said conveyor for movement therewith, means for moving said folders with a straight line movement above said supporting surface into and out of engagement with portions of said wrapper extending beyond the ends of said article to form end folds therein, and means for adjusting said folders to and from each other.

21. In a wrapping machine, a lifter table con-

structed and arranged to support an article partially encircled in a wrapper, said wrapper having ends projecting beyond the ends of said article, folder support brackets mounted on said table, end folders mounted on said brackets, means for moving said folders with a straight line movement into engagement with said projecting wrapper ends to form end folds in portions of said wrapper, creaser members movably mounted on said brackets, and means operative after the formation of said end folds and while said end folders are proximate the ends of said article for operating said members to flatten and crease other portions of said wrapper.

15 22. In a wrapping machine, a lifter table constructed and arranged to support an article partially encircled with a wrapper having end portions thereof extending beyond the ends of said article, brackets mounted on said table, a guide on each of said brackets, a slide on each of said guides, a folder bracket on each of said slides, an end folder mounted on each of said folder brackets, and means for moving said slides to cause said folders to move into and out of folding engagement with said wrapper ends and form end tucks therein.

23. In a wrapping machine, a lifter table constructed and arranged to support an article partially encircled with a wrapper having end portions thereof extending beyond the ends of said article, brackets mounted on said table, a guide on each of said brackets, a slide on each of said guides, a folder bracket on each of said slides, an end folder mounted on each of said folder brackets, means for moving said slides to cause said folders to move into and out of folding engagement with said wrapper ends and form end tucks therein, a creaser movably mounted on each of said folder brackets, and means for moving 30 40 said creasers to and from said table to crease portions of the wrapper located therebeneath.

24. In a wrapping machine having a lifter table, and an infeed conveyor for moving an article against a draped wrapper onto said lifter table and positioning said article on said table with said wrapper partially encircled about said article with portions of said wrapper extending unfolded beyond the ends of said article, opposed end folders mounted on said table, means for 45 moving said folders against said extending wrapper portion to form end folds therein, and independently movable means also carried by said table and movable with said end folders for flattening other portions of said wrapper projecting beneath said end folders and outwardly beyond the end of said article.

25. In a wrapping machine having a lifter table, and an infeed conveyor for moving an article against a draped wrapper onto said lifter table and positioning said article on said table with said wrapper partially encircled about said article with portions of said wrapper extending unfolded beyond the ends of said article, opposed end folders mounted on said table, means for 50 moving said folders against said extending wrapper portion to form end folds therein, creasers located adjacent said folders and movable therewith, means for moving said lifter table to a position of article discharge, means for moving said creasers into wrapper creasing relation with said table, yieldingly mounted pivoted folders adjacent said discharge position, and means carried by and associated with said folders for ironing down a portion of the unfolded wrapper.

CHARLES ARELT.
